UNITED STATES PATENT OFFICE

ALLEN E. KENNEDY, OF UTICA, NEW YORK

BOXING GLOVE

Application filed February 7, 1930, Serial No. 426,630. Renewed May 26, 1932.

This invention relates to boxing gloves and is more particularly concerned with the construction of the palm portion of the glove to provide an external grip for the fingers.

In gloves of this type as heretofore constructed, a single palm piece extending from above the grip to a point below the grip has been used and a separate grip strip traversing the palm has been applied over this one piece section, stitched thereto and padded with suitable material. With the body of the one-piece palm back of and stiffened by this grip the palm cannot conform to the natural contour of the hand and the interior of the glove, particularly the finger holding portion, cannot be adequately ventilated. And since the palm, because of the interposed body of the one piece palm, and the overlying grip, cannot conform to the natural contour of the hand when flexed to grip, the glove does not adequately adjust itself to the knuckles.

One object of the present invention is the construction of the palm of the glove to provide a grip with the palm conforming to the contour of the hand, more easily flexible to grip and adequately ventilated.

Another object of the invention is to effect these results by a construction facilitating manufacture with economies in manufacturing costs accompanied by improved fit and comfort in the glove itself.

These objects are attained in accordance with the present invention, by forming the palm of the glove as separate upper and lower sections spaced and joined by a palm traversing grip lapping over and joined to the outer faces of the spaced abutting edges of the upper and lower sections. By thus piecing the palm, I eliminate that integral palm portion which formerly under lay the grip and formed surplusage preventing conformation of the glove palm to the natural conformation of the hand and restricting the flexing of the palm by the hand, and in so doing I

am enabled to construct the palm portion more economically.

Preferably the lower palm section which, as usual forms the lacing portion, instead of being formed of one piece, slit and edge bound, is made in two complementary pieces abutting and laced together along the longitudinal median line of the palm, since this facilitates the application of the binding or edging and the formation of the lacing holes or eyelets and enables smaller and therefore less expensive pieces of leather to be used for this purpose.

The grip which traverses the glove palm is in the form of a single strip of leather or other material of greater width than the spacing between the upper and lower palm sections to provide protuberant fullness and is stuffed from the interior of the palm portion, a light flexible fabric lining which conveniently may extend to the tip of the glove being stitched at its lower end to the inner faces of the spaced abutting ends of the upper and lower palm sections to form the back of the grip and to retain the stuffing therein as well as provide a lining for the interior of the glove. This lining, being of relatively light flexible fabric, will not resist free flexing of the glove palm and conformation of the inner face of the palm to the contour of the fingers and palm of the hand.

The invention consists in the construction, arrangement and combinations of parts herein described and claimed and will be more clearly apparent from the following detailed description which is to be read in conjunction with the accompanying drawing forming part thereof and in which:

Figure 1 is a view in elevation of the palm face of a boxing glove constructed in accordance with the present invention.

Figure 2 is a plan view of the component parts of the glove palm, including the grip strip, separated and in their associated relation.

Figure 3 is a plan view of the same parts assembled and stitched together with filling applied to the grip and with the tip end of the lining backing the grip shown.

5 Figure 4 is a longitudinal section through the assembled palm shown in Figure 3, taken on the line 4—4 of Figure 3.

10 Figure 5 is a detail of the strip of lining applied to the under face of the palm and backing the grip strip.

15 Aside from the construction of the palm portion, the glove shown in Figure 1 may be of any suitable form. As shown in Figure 1, the back is extended over the upper end 20 of the glove to its inner face as a tip 1 curved in the manner shown in Figure 1 and shirred as shown, the lower edge of the tip 1 being joined to the upper edge of the upper end section of the palm constituting more particularly the subject of the present invention, and the sides of the back extending to and joining the outer side edges of this palm, as in the usual glove construction.

25 My improved palm is formed as upper and lower portions horizontally separated and spanned and joined by a palm traversing finger grip. The upper section 2 (Fig. 2) has a curved transverse upper edge 3, which is stitched to the lower edge of the shirred over folded top 1 of the glove back, and a straight horizontal lower edge 4. This upper portion 2 may be termed the finger end portion. Its lower straight edge 4 is spaced longitudinally or vertically of the palm from the upper straight edge of a lower or lacing portion which, as shown, and as preferable, is in the form of complementary sections 5 and 6 having abutting longitudinal lacing edges 7 extending substantially in the longitudinal median line of the palm. These edges and the bottom edges of the sections 5 and 6 are protected by binding 8 stitched thereto. The binding extends up to the upper transversely alined horizontal upper edges 9 of the sections 5 and 6 which are in parallel with and determinately spaced from the opposed lower edge 4 of the upper or finger end portion 2. The lower ends of the sections 5 and 6 are intended to overlie the wrist and may, if desired, have an additional layer of leather or other fabric stitched thereto as a reinforcement as suggested in Figures 2 and 3. One of the lacing sections, as shown, section 6, is incut at its outer side, as at 10, Fig. 2, to receive a thumb section 11, and the edges of both sections outwardly of the binding 8 are perforated to receive the usual lacing 12 (Fig. 1).

60 The described upper and lower palm sections are transversely divided and spaced at a point in the length of the hand which may be selectively variable but which I prefer to locate substantially in the line of the finger bend in the natural closing of hand in the

glove, i. e., in the line of the bend of the middle joints of the four fingers.

The upper and lower edges of their abutting spaced edges are spanned and connected by palm traversing finger grip which is 70 formed by a transverse strip 13 of leather or other suitable material of substantially greater width than the spacing of said edges to provide protuberant fullness, this strip having its upper and lower edges stitched to and 75 connecting the spaced abutting edges 4 and 9 of the upper and lower palm sections.

80 Since the lacing edges 8 extend to the under side of the grip 13, air may penetrate to the area occupied by the fingers of the glove 85 inserted hand and the glove may be freely flexed since there is no thickness of palm in back of the grip to cramp and restrain free flexure of the palm. The grip 13 protrudes outwardly from the face of the palm as indicated in Figure 4 and is held in this protuberant position by a filling or stuffing 14 of hair, 90 felt or other suitable substance. The grip strip 13 is backed and a pocket is formed therewith to receive the stuffing 14 by means of the flexible inner lining 15 of canvas for the glove tip, this lining having its lower end overlying the inner faces of the upper and lower palm portion at their abutting edges and stitched to and connecting said edges. 95 This lining, being, for example of light flexible fabric, does not materially restrict the flexing of the palm as would the leather material of the palm if an integral portion of the palm were employed as a backing for the 100 grip, and being porous, will afford some ventilation of the fingers extending there above.

105 With the freedom for flexure afforded by a sectional palm with sections spaced at the grip, the knuckles are free to adjust themselves in the glove back and increased comfort and fit are thus secured.

The palm construction involved herein is adaptable generally to all types and constructions of boxing gloves and while the form 110 disclosed herein represents a preferable arrangement and construction of the palm, it is intended as illustrative only, of the invention and not as restrictive of its structure, and is subject to variation and modification to suit 115 different conditions of manufacture and use in consonance with the spirit of the invention and scope of the appended claims.

I claim:

120 1. A boxing glove having a palm portion horizontally divided and separated at its upper finger end to provide upper and lower portions spaced apart, a palm traversing grip strip spanning and joining the spaced palm portions on their external faces, and a flexible 125 lining underlying said palm portions and said grip strip and secured to the edges of the palm portions and said strip providing a filling retaining pocket to form the grip.

130 2. A boxing glove palm comprising hori-

zontally separated upper and lower sections, a palm traversing finger grip spanning the space between and joining said sections, said grip being in the form of a single strip of material of greater width than the space between the upper and lower palm sections to provide protuberant fullness when stuffed, a light flexible fabric lining stitched to the inner faces of the spaced abutting ends of the upper and lower palm sections to form the back of the grip and to retain the stuffing in the grip and permit free flexing of the glove palm, said upper section having a curved upper edge for connection with a glove back and a straight horizontal lower edge.
